METHOD OF AND MACHINE FOR TURNING
THE PLATFORM COVERS OF PLATFORM
SHOESEugene J. Ray, Beverly, Mass., assignor to United
Shoe Machinery Corporation, Flemington,
N. J., a corporation of New Jersey

Application June 24, 1944, Serial No. 541,866

30 Claims. (Cl. 12—1)

1

This invention relates to methods of and machines for turning the platform covers of platform shoes. For a disclosure of this type of shoe reference may be had to United States Letters Patent No. 2,341,675, granted February 15, 1944, on an application filed in the name of John J. Walsh. Such shoes are characterized by a relatively thick midsole or platform interposed between the insole and the outsole and having its edge covered with sheet material which has first been stitched to the upper and the insole and which is later laid and secured under the edge of the platform. Before the cover can be laid and secured under the platform, however, it must first be turned-down from the upright position in which it was stitched. The operation of turning the cover is often performed after a last has been inserted in the shoe and after the platform has been applied. Inasmuch as the cover usually hugs the upper of the shoe tightly, the cover cannot be turned without considerable difficulty and often it can be turned only by the use of pincers. In any case, the operation as heretofore carried out is laborious and time-consuming.

It is an object of the present invention to provide a method whereby platform covers may be easily and quickly turned. This method, as will presently be shown, may be carried out by applying a force heightwise against the bottom of the shoe in opposition to an oppositely directed force applied simultaneously at separated localities of the margin of the platform cover. The margin of the cover may, as disclosed herein, be bent outwardly to facilitate the rolling back of the cover upon itself.

A further object of the invention is to provide a machine for turning platform covers. In accordance with this object, the machine disclosed herein is provided with means for gripping the margin of a platform cover and with means for effecting a relative movement between the shoe and the gripping means in a direction heightwise of the shoe to turn the cover down. The illustrative machine shown herein is provided with gripper jaws for holding the margin of the cover and with a movable abutment in the form of a plunger which pushes against the bottom of the shoe to move the shoe bodily heightwise while the gripper jaws hold the margin of the cover in opposition to the movement of the shoe to cause the cover to be turned down. The gripper jaws, furthermore, are so manipulated as to turn the margin of the cover outwardly to facilitate its rolling back upon itself. The illustrative machine is

2

provided with means for moving the plunger and for closing the gripper jaws in timed relation.

These and other novel features of the invention are illustrated in the accompanying drawings and hereinafter described and claimed.

Referring to the drawings,

Fig. 1 is a side elevation of a machine embodying the invention;

Fig. 2 is a front elevation, partly in section, 10 of the upper portion of the machine;

Fig. 3 is a large scale rear elevation of the cover gripping instrumentalities at the beginning of their operation;

Fig. 4 is a sectional view taken on the line 15 IV—IV of Fig. 2;

Fig. 5 is a sectional view taken on the line V—V of Fig. 2;

Fig. 6 is a large scale sectional view taken on the line VI—VI of Fig. 1;

Fig. 7 is a front elevation of the parts shown in 20 Fig. 6;

Fig. 8 is a side elevation of the parts shown in Figs. 6 and 7;

Fig. 9 is a large scale front elevation of one of 25 the pincer units;

Fig. 10 is a corresponding side elevation of the parts shown in Fig. 9;

Fig. 11 is a side elevation of the heel end of a 30 shoe at the beginning of the operation;

Fig. 12 is a view similar to Fig. 11 showing a later stage of the operation;

Fig. 13 is a view similar to Fig. 12 showing a still later stage of the operation;

Fig. 14 is a plan view of the heel end of the 35 inverted shoe showing the operation at the stage indicated in Fig. 13;

Fig. 15 is a view similar to Fig. 13 showing the position of the platform cover at the end of the operation; and

Fig. 16 is a view in front elevation, looking at the heel end of the shoe, showing the position of the platform cover at the end of the operation.

The operating instrumentalities of the illustrated machine consist of two pairs of pincer jaws 45 20 and 22 (Fig. 2) for gripping and turning the marginal portion of a platform cover, and a presser head 24 which engages the shoe bottom and pushes the shoe while the cover is gripped by the pincers to complete the turning of the cover. The supporting structure of the machine consists of an upright hollow housing or frame 26 which rises from a base 28 and which carries a pair of upwardly extending side plates 30 and 50 32.

The pairs of jaws 20 and 22 are carried by a

swinging frame or block 34 having a pair of arms 36 and 38 which are supported for rotation about an axis passing approximately through the tips of each of the pairs of pincer jaws when the jaws are closed. The arm 36 terminates in a hub 40, and the arm 38 terminates in a hub 42, said hubs being fixed by screws 43 to a pivot in the form of a pair of trunnion pins 44 and 46, respectively. These trunnion pins are journaled in bearings 48 and 50 which, in turn, are carried by the side plates 30 and 32, respectively. A more detailed description of the jaw mechanism will be given later.

The presser head 24 consists of a flat plate (Figs. 13 and 14) having a rounded end to conform generally to the end of a shoe bottom. It is secured by a screw 23 to a lug 25 formed on a horizontally offset portion 52 of a downwardly extending rod or shank 54 (Figs. 2 and 4). The screw 23 is threaded into the head 24 and extends through a slot formed in the lug 25 in a direction to provide for adjustment of the head lengthwise of the shoe. A tongue-and-groove connection 55 (Fig. 16) maintains the head 24 in proper alignment on the lug 25. The shank 54 is slidable heightwise in a tubular guideway 56 supported by a shelf 60 that connects the side plates 30 and 32. The offset portion 52 extends through a slot 53 formed in the wall of the tubular guideway 56. The slot 53 has a spiral portion which operates as a cam to turn the head 24 outwardly to an out-of-the-way position when the shank rises and to turn the head inwardly to a position wherein it may engage the shoe bottom as the shank descends. The head 24, offset 52, and shank 54 constitute a unitary assembly which will later be referred to as a plunger. A compression spring 58 (Fig. 4) surrounding the plunger shank 54 has its lower end in abutting engagement with a bushing 61 secured in the lower portion of the guideway 56. The upper end of the spring 58 is in abutting engagement with a collar 62 secured to the shank 54 and slidable with the shank in the guideway. The thrust of the spring normally maintains the shank in an upper position determined by a collar 64 secured upon the lower end of the shank and engaging the lower end of the guideway 56.

The power for operating the above-mentioned instrumentalities is derived from a treadle 66 (Fig. 1) pivotally mounted upon a fulcrum pin 68 secured in a pair of spaced upright frame members 84 and 86 (Figs. 6, 7 and 8) which are bolted to the base 28 of the housing. Journaled in the treadle 66 at an intermediate portion thereof is a pulley 70 about which is looped a cable 72 one end portion of which extends upwardly and is anchored to a pin 74 secured in the housing 26 while the other end, also extending upwardly, passes partly around and is secured to a pulley 76 by a clamp 77 (Fig. 8). A shaft 78 carries the pulley 76 and is journaled in bearings 80 and 82 formed in the upright frame members 84 and 86 (Fig. 7).

Also carried upon the shaft 78 is a pulley 88 to which one end of a cable 90 is secured by a clamp 91. The cable 90 extends upwardly over a pulley 92 (Figs. 1 and 2) and then downwardly, a weight 94 being secured to the downwardly extending end of the cable. Swinging movement of the weight 94 is prevented by stationary guides having flanges 95 which are slidably engaged by grooves formed in the sides of the weight. The pulley 92 is mounted for free rotation on a bolt carried by a bracket 96 (Fig. 2) secured to and

depending from the shelf 60. The shaft 78 also carries a pair of cams 98 and 100 (Figs. 1 and 8). These cams, as well as the pulleys 76 and 88, are secured to the shaft 78 so that the shaft, the two cams, and the two pulleys all rotate as a unit.

Secured in the frame members 84 and 86 is a crosspin 102 which serves as a fulcrum for a pair of arms 104 and 106 (Fig. 6). Carried by the arm 104 (Fig. 8) is a cam roll 108 which engages the periphery of the cam 98 to control the movement of the arm 104. The arm 106 carries a roll 110 which engages the periphery of the cam 100 to control the movement of the arm 106. Secured by a block 111 pivoted in the outer or forward end of the arm 104 is the lower end of a cable 112 the upper end of which is secured to a pulley 114 (Fig. 2) mounted on the hub 40. Also mounted on the hub 40 and adjacent to the pulley 114 is a pulley 116 to which is secured the upper end of a chain 118 having its lower end secured to the upper end of a tension spring 120. The lower end of the spring 120 is secured to a pin 122 which is fastened to the housing 26. It is evident that the tension of the spring 120 operating through the chain 118 will exert an upward pull on the cable 112, tending to maintain the roll 108 against the cam 98 and the frame 34 in a position of rotation determined by a stop 121 (Figs. 1 and 8) formed on the cam 98. The stop 121 consists of an extension which, when engaged by the roll 108, will positively prevent further rotation of the cam under the influence of the weight 94.

Pivotedly mounted in the outer or forward end 35 of the arm 106 is a block 123 to which is secured the lower end of a cable 124. The upper end of the cable 124 is secured to a tension spring 126 (Fig. 2) which, in turn, is secured to the lower end of the rod 54.

40 The pincer jaws 20 (Figs. 3, 9 and 10) are carried by a supporting block 128 which is hinged upon a pintle 130. The pincer jaws 22 are similarly mounted in a supporting block 132 which is hinged upon a pintle 134. The pintles 130 and 134 are both mounted in pairs of ears 133 extending from a plate 135 which, in turn, is rigidly secured to the bracket 34. The pintles 130 and 134 are parallel and extend in a direction which is longitudinal with respect to the gripper, jaws that 50 is, with respect to the shanks of the gripper jaws when the jaws are closed.

The two pairs of pincers are similar and only one will be described in detail. The pincer 20, for example, consists of a relatively stationary 55 jaw 136 integral with the support 128 and a relatively movable jaw 138 fulcrumed upon a pin 140 secured between ears 141 extending from the support 128. The jaw 138 has a flat serrated terminal portion 137 of triangular outline for gripping 60 the work against a similar terminal portion of the jaw 136. Inasmuch as the jaw 136, at the beginning of the operation, must be between the platform cover and the last (or the shoe upper), its terminal gripping portion has a wedge-shaped 65 extension 139 to facilitate the introduction of the work. The movable jaw 138 has a depending tail 142 which is engaged by a cam surface 144 on a wedge-shaped cam 146 mounted for longitudinal movement in a guideway of the support 128 and 70 retained therein by a cover plate 148. The cam 146 has a shank 150 the lower end of which has an offset portion 160. Secured in this offset portion 160 is a pin 162 having a rounded or knob-shaped head. Interposed between one of the 75 pintles 130 and the offset

160 is a weak compression spring 164 which tends to maintain the cam 146 down in its inoperative position. While the operating cam is thus held down, the jaw 138 is held in open position by a light, relatively weak torsion spring 166. The compression spring 164 serves also as a torsion spring (Fig. 3), having outwardly extending end portions 167 which bear against the plate 135 and the shank 150, respectively, to maintain the gripper jaw assembly yieldingly in a stopped position of rotation about the axis of the pintle 130, as shown in Fig. 3. In the illustrated machine, this stopped position is determined by the block 128 striking against the edge of the plate 135.

The pincer 22 has similar parts, including a pin 168 (Fig. 3) which is like the pin 162. An equalizing bar 170 is fulcrumed at its middle portion upon a pin 172 carried by a pair of ears 174 which extend upwardly from a lever 176 (see also Fig. 5). The equalizing bar 170 has its end portions bearing against the knob-shaped heads of the pins 162 and 168. The lever 176 is fulcrumed upon a pin 178 secured in the arm 36. The arm 38 has formed in it a guideway for guiding a slide 180 in a path which is radial with respect to the axis of the trunnions 44 and 46. The upper end of the slide 180 carries a cam roll 182 (Figs. 3 and 5) which engages the periphery of a stationary cam 184 mounted upon lugs extending from the side plate 32, and the lower end of the slide is notched to receive the free end of the lever 176. A pin 185 retains the lever 176 within the notched portion of the slide 180. A tension spring 186 (Fig. 3) anchored at its upper end in the plate 135 and secured at its lower end to a lug extending from the ear 174 yieldingly maintains the cam roll 182 against the cam 184. The spring 186 is strong enough, when permitted by the cam 184, to overcome the springs 164 and 166. As shown in Fig. 5, the cam 184 has a rise 188 at the bottom, a rise 190 at the top, and a low intermediate portion.

The operation of the above-described machine and the manner of performing the above-mentioned method upon a shoe will now be explained. The shoe, which is shown as mounted upon a last L, comprises a platform sole P having a wedge heel W cemented to one face and a sock lining S cemented to its other face. Stitched to the sock lining S close to the edge of the platform sole P is a platform cover C. Although the illustrated shoe is of the open heel type wherein the rear portion of the upper consists merely of a heel strap, it should be understood that the following explanation applies also to ordinary closed-back shoes. The cover C may, as shown in Fig. 11, have a coating of adhesive A along its margin to secure the cover in position after it has been lasted under the platform by a subsequent operation. A similar coating of adhesive A' may be applied to the wedge heel W. An outsole (not shown) will be applied later.

The operator presents the heel end of the shoe by hand to the machine, holding the shoe inverted and manipulating it to insert the tips 139 of the stationary jaws 136 between the cover C and the upper U (or the last L if the upper is entirely cut away at that locality). This stage of the operation is shown in Figs. 3 and 11. He then depresses the treadle 66 and causes rotation of the cam shaft 78 in a direction indicated by the arrow in Fig. 1. The first effect of the rotation of the cam 98 is to swing the pincer frame 34 in a clockwise direction, as viewed in Fig. 5, causing the cam roll 182 to roll down the rise 188 at the

bottom of the cam 184 and thereby to permit the spring 186 yieldingly to close the movable jaws 138 of the pincers. Both pincer units 20 and 22 are thus closed to grip the margin of the cover at separated localities. While the pincers are closing, rotation of the cam 100 moves the plunger rod 54 down in the guide tube 56, the guide slot 53 causing the plunger to turn and swing the plunger head 24 from the position shown in Fig. 4 to a position directly above the shoe bottom. This movement of the plunger, which serves merely to bring the plunger head into operating position, takes place quickly. By the time the pincer jaws have closed to grip the work, the head 24 has come down into engagement, or almost into engagement, with the shoe bottom. Continued depression of the treadle causes further swinging movement of the pincer frame 34 and it also causes the plunger head 24 to begin a slow downward operating stroke. The swinging movement of the pincer frame continues until the cam roll 182 comes almost to the rise 190 at the top of the cam 184, causing the pincers to bend the margin of the cover outwardly and thereby to turn the margin of the cover C from the position shown in Fig. 11 through the positions shown in Figs. 12 and 13 to the position shown in Fig. 15. It will be observed that the pincer frame, while pivotally mounted in the bearings 48 and 50, is held against translatory movement, and that the pincers themselves are therefore held against translatory movement. Since the axis of the trunnion pins 44 and 46 passes approximately through the tips of the pincer jaws, the swinging movement of the pincers will be outward or away from the last. The pintles 130 and 134 permit the pincer units 20 and 22 to turn in response to the increasing tension in the margin of the cover C. Without such freedom of pivotal movement about the pintles 130 and 134, the pincer units might develop an excessive tension in that portion of the cover that lies between them as they turn the margin of the cover over. The cam 98 is designed to cause the pincer frame 34 to dwell with the roll 182 just below the rise 190.

While the marginal portion of the cover is thus being rolled over by the pincers, the downward stroke of the plunger head 24 moves the body portion of the shoe down to pull the cover through the position shown in Fig. 13. The cam 100 is designed to continue the downward yielding pressure of the plunger until the pincer frame 34 reaches the dwell position above mentioned. The cover, as shown in Figs. 15 and 16, is now completely turned and is stretched tight with a tension determined by the spring 126.

Continued depression of the treadle 66 serves to relieve the downward pressure of the plunger head 24 while the pincers remain stationary for a short while in their dwell position. This relief of pressure on the shoe bottom is obtained by a slight depression in the cam 100; and the plunger, while it may rise slightly, does not travel far enough up the slot 53 to turn to its out-of-the-way position. The plunger now begins a brief dwell while the pincer frame 34 resumes its swinging movement, causing the roll 182 to ride up on the cam rise 190 and open the pincer jaws to release the shoe.

Downward movement of the treadle 66 is stopped by engagement of the treadle with the base 28 of the machine before the cam shaft 78 has made a complete revolution. The operator then releases the treadle and thereby permits

the weight 94 to rotate the cam shaft 78 in a counterclockwise direction until all the parts of the machine have retraced their movements and arrived at their initial positions.

After the heel portion of the cover C has thus been turned, the operator presents the toe end of the shoe to the machine and in a similar manner turns the toe end. The portions of the cover between the ends of the shoe will either turn naturally with the end portions or will offer substantially no resistance to turning by hand after the end portions have been turned.

The operation may, if desired, be performed first upon the toe end of the cover and then upon the heel end.

Having described my invention, what I claim as new and desire to secure by Letters Patent of the United States is:

1. The method of turning the platform covers of platform shoes which consists in holding the margin of the platform cover of a shoe at separated localities adjacent to an end of the shoe while said margin is directed toward the top of the shoe and in bodily moving the shoe heightwise by pressure applied to the shoe bottom while the margin of the cover is thus held to reverse the direction of said margin relatively to the shoe.

2. The method of turning the platform covers of platform shoes which consists in holding the margin of the platform cover of a shoe at separate localities, in bodily moving the shoe heightwise by pressure applied to the shoe bottom while the margin of the cover is thus held, and in turning outwardly the margin of the cover to facilitate the rolling back of the cover upon itself as the cover is being turned.

3. The method of turning the platform covers of platform shoes which consists in gripping the margin of a platform cover of a shoe at different localities at one end of the shoe while said margin is directed toward the top of the shoe and in causing relative heightwise movement between the body of the shoe and the margin of the cover while the margin is thus gripped to reverse the direction of said margin relatively to the shoe, and in repeating this operation at the other end of the shoe.

4. A machine for turning the platform covers of platform shoes comprising a gripper for gripping the margin of a platform cover of a shoe while it lies against the upper of the shoe, an abutment engageable with the bottom of the shoe, and means for moving said abutment against the bottom of the shoe to move the shoe while maintaining the gripper in gripping engagement with the margin of the cover to turn the cover and cause its margin to extend away from the shoe bottom in the opposite direction.

5. A machine for turning the platform covers of platform shoes comprising means for gripping the margin of a platform cover of a shoe, an abutment engageable with the shoe bottom, a treadle, and mechanism operated by said treadle for causing the gripping means to grip a work piece and for causing relative movement between the gripping means and the abutment in a direction heightwise of the shoe to turn the cover while the work piece is thus gripped.

6. A machine for turning the platform covers of platform shoes comprising a pair of jaws for gripping the margin of a platform cover of a shoe, an abutment engageable with the bottom of the shoe, means for moving said abutment against the bottom of the shoe to cause heightwise movement of the shoe while maintaining

the jaws in gripping engagement with the margin of the cover to turn the cover, and means for turning the jaws to roll the cover back upon itself as the cover is being turned.

5 7. A machine for turning the platform covers of platform shoes comprising a pair of jaws for gripping the margin of a platform cover of a shoe, an abutment engageable with the bottom of the shoe, and means for closing the jaws 10 to cause them to grip the margin of the cover while said margin extends from the shoe bottom toward the top of the shoe and for moving said abutment against the shoe bottom in timed relation to the closing of the jaws while maintaining the jaws in gripping engagement with the margin of the cover to turn the cover and cause said margin to extend away from the shoe bottom in the opposite direction.

15 8. A machine for turning the platform covers of platform shoes comprising a pair of pivotally connected jaws for gripping the margin of a platform cover of a shoe, a support for said jaws, an abutment engageable with the bottom of the shoe, means for closing the jaws to cause them to grip the margin of the cover and for causing relative movement heightwise of the shoe between the abutment and the gripping jaws to turn the cover, and a pivotal mounting for the support arranged to enable the jaws to swing outwardly to facilitate the rolling back of the cover upon itself as it is being turned.

20 9. A machine for turning the platform covers of platform shoes comprising a pair of pivotally connected jaws for gripping the margin of a platform cover of a shoe, a block upon which said jaws are supported, an abutment engageable with the bottom of the shoe, means for closing the jaws to cause them to grip the margin of the cover and for causing relative movement heightwise of the shoe between the abutment and the gripping jaws to turn the cover, and means for swinging said block to cause the jaws to roll the cover outwardly and back upon itself as it is being turned.

25 10. A machine for turning the platform covers of platform shoes comprising a pair of pivotally connected jaws for gripping the margin of a platform cover of a shoe, a block upon which said jaws are supported, an abutment engageable with the bottom of the shoe, means for closing the jaws to cause them to grip the margin of the cover, means for causing the abutment to push against the shoe bottom while the jaws are holding the margin of the cover to turn the cover, and means for swinging said block outwardly of the shoe about an axis which passes approximately through the tips of the jaws to facilitate the rolling back of the cover upon itself as it is being turned.

30 11. A machine for turning the platform covers of platform shoes comprising a pair of pivotally connected jaws for gripping the margin of a platform cover of a shoe, a block upon which said jaws are supported, a pivotal mounting for said block having its axis passing approximately through the tips of the closed jaws, an abutment engageable with the bottom of the shoe, means for causing the abutment to push against the shoe bottom and for swinging the block outwardly of the shoe about said pivotal mounting, a stationary cam, and mechanism on said block operated by the cam to cause the jaws to close as the block swings, the swinging movement of the block serving to facilitate the rolling back 35 on itself of the platform cover while the closed

jaws hold the margin of the cover and while the abutment moves the shoe to turn the cover.

12. A machine for turning the platform covers of platform shoes comprising a pair of pivotally connected jaws for gripping the margin of a platform cover of a shoe, a block upon which said jaws are supported, trunnion bearings upon which said block is pivotally mounted for swinging movement about an axis passing approximately through the tips of the jaws, a plunger engageable with the bottom of the shoe, means for causing the plunger to push against the shoe bottom and for swinging the block outwardly of the shoe about said axis, a spring tending to close the jaws, a stationary cam, and mechanism on the block co-operating with the cam normally to hold the jaws open against the force of said spring, said cam being designed to permit the spring to close the jaws during the beginning of the swinging movement of the block, whereupon the jaws will grip the margin of the cover and then turn the margin of the cover outwardly as the block swings and while the plunger pushes the shoe to complete the turning of the cover.

13. A machine for turning the platform covers of platform shoes comprising means for gripping the margin of a platform cover of a shoe, means engageable with the shoe bottom for pushing the shoe to cause the cover to be turned while the margin of the cover is held by the gripping means, and a common mechanism for operating said gripping means and said pushing means, said mechanism including a cam through which the gripping means is operated and a cam through which the pushing means is operated, said cams being designed to cause the gripping means and the pushing means to operate in timed relation to each other.

14. A machine for turning the platform covers of platform shoes comprising means for gripping the margin of a platform cover of a shoe, means engageable with the shoe bottom for pushing the shoe to cause the cover to be turned while the margin of the cover is held by the gripping means, a shaft, means for turning said shaft, a pair of cams secured on said shaft for rotation therewith as a unit, mechanism operated by one of said cams for closing the gripping means, and mechanism operated by the other cam for causing the pushing means to exert a thrust against the shoe bottom.

15. A machine for turning the platform covers of platform shoes comprising means for gripping the margin of a platform cover of a shoe, means engageable with the shoe bottom for pushing the shoe to cause the cover to be turned while the margin of the cover is held by the gripping means, a trunnion support upon which the gripping means is mounted for swinging movement, means for swinging the gripping means outwardly of the shoe to turn the cover back upon itself and for causing the pushing means to exert a thrust against the shoe bottom to complete the turning of the cover, a stationary cam, and mechanism carried by the gripping means and co-operating with said stationary cam to cause said gripping means to close at the beginning of the swinging movement of the gripping means.

16. In a machine for turning the platform covers of platform shoes, a pair of jaws for gripping the margin of a platform cover, a pivotal connection between said jaws to provide for opening and closing movements, a rigid support for said jaws, and a hinge between said jaws and said

support for enabling said jaws to turn about an axis which extends longitudinally of the jaws.

17. In a machine for turning the platform covers of platform shoes, two pairs of jaws for gripping the margin of a platform cover of a shoe at spaced localities, a common rigid support for said pairs of jaws, and a hinge between each pair of jaws and said support, said hinge having parallel axes extending in a direction to permit turning of each set of jaws in response to the tension of the cover.

18. In a machine for turning the platform covers of platform shoes, a pair of jaws for gripping the margin of a platform cover, a pivotal connection between said jaws to provide for opening and closing movements, a support for said jaws, and a pivotal mounting for said support having its axis extending approximately through the tips of the jaws in a direction transverse to the jaws to permit the jaws to make a swinging movement to turn the margin of the platform cover outwardly.

19. In a machine for turning the platform covers of platform shoes, two pairs of jaws for gripping the margin of a platform cover of a shoe at spaced localities, a common support for said jaws, a trunnion mounting for said support having its axis extending approximately through the tips of the jaws, and means for swinging said support about said trunnion mounting to cause the jaws to turn the margin of the platform cover outwardly.

20. A machine for turning the platform covers of platform shoes comprising two pairs of jaws for gripping the margin of a platform cover of a shoe at spaced localities, a common support for said pairs of jaws, and means for effecting a relative movement between the shoe and the support in a direction heightwise of the shoe to turn the cover.

21. A machine for turning the platform covers of platform shoes comprising two pairs of jaws for gripping the marginal portion of a platform cover of a shoe at spaced localities, a common support for said pairs of jaws, a plunger engageable with the bottom of the shoe, and means for causing said plunger to push the shoe heightwise while the marginal portion of the cover is held by said jaws.

22. A machine for turning the platform covers of platform shoes comprising two pairs of jaws for gripping the margin of a platform cover of a shoe at spaced localities, a block on which said pairs of jaws are mounted, a pair of trunnions upon which said block is mounted for swinging movement about an axis which passes approximately through the tips of the jaws of each pair when the jaws are closed, means for closing the jaws to cause them to grip the cover, means for turning the block about said trunnions to change the direction in which the jaws point and thereby to cause the jaws to turn the margin of the cover outwardly, and means for pushing against the shoe bottom while the cover is gripped by the jaws to complete the turning of the cover.

23. In a machine for turning the platform covers of platform shoes, a carrier, a relatively stationary gripper jaw mounted on said carrier, a relatively movable gripper jaw pivotally mounted on said carrier to open and close relatively to the stationary jaw, a weak spring tending normally to maintain said movable jaw open, said movable jaw having a tail, a slide mounted in a guideway in the carrier, said slide having a wedge-shaped end which engages the tail of the movable

jaw to close the jaw, a strong spring tending to urge said slide into jaw-closing position, and operating means constructed and arranged normally to hold said slide out of jaw-closing position and to permit said spring at the beginning of the operation to move the slide yieldingly into jaw-closing position.

24. In a machine for turning the platform covers of platform shoes, a carrier, a gripping mechanism comprising a relatively stationary gripper jaw mounted on said carrier, a relatively movable gripper jaw pivotally mounted on said carrier to open and close relatively to the stationary jaw, a weak spring tending normally to maintain said movable jaw open, said movable jaw having a tail, a slide mounted in a guideway in the carrier, said slide having a wedge-shaped end which engages the tail of the movable jaw to close the jaw, and a weak spring normally holding said slide out of jaw-closing position, a second gripping mechanism similar to the first-mentioned gripping mechanism and spaced therefrom, with the slides of both mechanisms parallel to each other, an operating member, an equalizing bar pivotally mounted at its middle portion on said operating member and engaging near its ends the ends of the slides opposite to the wedge-shaped ends, a strong spring tending to cause said operating member to exert a thrust through the equalizing bar upon each of the slides to urge the slides into jaw-closing position, means for normally holding said operating member against said strong spring, and means for releasing the operating member to the action of the strong spring to operate the gripping mechanisms.

25. In a machine for turning the platform covers of platform shoes, a plunger having a shank and a head offset from said shank for engaging a shoe bottom, and a tubular guideway in which the shank is movable longitudinally, said guideway having a cam slot in its wall, and means on said plunger engaging said slot to turn the plunger as the shank moves longitudinally in the guideway, said slot being shaped to swing the head from an out-of-the-way position into a position wherein the head may engage the shoe as the shank is moved longitudinally to move the head toward the shoe bottom.

26. In a machine for turning the platform covers of platform shoes, a plunger having a shank and a head offset from said shank for engaging a shoe bottom, and having also a connecting portion between the head and the shank, a cylindrical guideway in which the shank is movable longitudinally, said guideway having a slot in its wall through which the connecting portion of the plunger extends, said slot being shaped to turn the plunger and thereby to swing the head from an out-of-the-way position into a position wherein it may engage a shoe bottom as the shank is

5 moved longitudinally, a spring acting upon the plunger normally to maintain the shank in said out-of-the-way position in said guideway, and means for moving said shank longitudinally in said guideway to bring the head into operative engagement with a shoe bottom.

27. A machine for turning the platform covers of platform shoes comprising means for gripping the margin of the platform cover of a shoe, a pivotal mounting for said gripping means, means for turning the gripping means about said pivotal mounting to bend outwardly the margin of the platform cover to partially turn the cover, and means for effecting relative heightwise movement between the gripping means and the shoe to complete the turning of the cover.

28. A machine for turning the platform covers of platform shoes comprising a pair of jaws for gripping the margin of a platform cover of a shoe, a support for holding said jaws against translatory movement, and means operable while the margin of the cover is gripped by said jaws to move the shoe in a direction to cause the cover to be turned.

29. A machine for turning the platform covers of platform shoes comprising a pair of jaws for gripping the margin of a platform cover of a platform shoe, a support for holding the jaws against translatory movement, a pivot in said support for enabling the jaws to perform a rotary movement, and means operable while the margin of the cover is gripped by said jaws to move the shoe in a direction to cause the cover to be turned.

30. A machine for turning the platform covers of platform shoes comprising a pair of jaws for gripping the margin of a platform cover of a shoe, a support for holding said jaws against translatory movement, a pivot in said support for enabling said jaws to perform a rotary movement in the direction in which the platform cover bends while turning, means for causing the jaws to perform said rotary movement about said pivot to roll the cover back upon itself, and means operable while the margin of the cover is gripped by said jaws to move the shoe in a direction to cause the cover to be turned.
